VANIA.

DESIGN FOR A LIGHT SHADE OR SIMILAR ARTICLE.

Application filed December 16, 1926. Serial No. 20,063. Term of patent 14 years.

To all whom it may concern:

Be it known that I, FRED W. STEWART, a citizen of the United States, residing at Pittsburgh, Allegheny County, Pennsylvania, have invented a new, original, and ornamental Design for Light Shades or Similar Articles, of which the following is a specification, reference being had to the accompanying drawings, forming part thereof.

Figure 1 is a front perspective view of a light shade or similar article, showing my new design.

Figure 2 is a side elevation of the article, shown in Figure 1.

The light shade or similar article is preferably in the form of a container and is preferably translucent so that it is adapted to contain an electric light bulb, the light passing outwardly therethrough.

I claim:

The ornamental design for a light shade or similar article, substantially as shown and described.

In testimony whereof I have hereunto set my hand.

FRED W. STEWART.
